Charles Gunnar Molin
BY *Carl Benjamin*
his ATTORNEY,

UNITED STATES PATENT OFFICE.

CHARLES GUNNAR MOLIN, OF BROOKLYN, NEW YORK.

MEASURING APPARATUS FOR LIQUIDS.

SPECIFICATION forming part of Letters Patent No. 398,528, dated February 26, 1889.

Application filed October 24, 1888. Serial No. 289,027. (No model.)

To all whom it may concern:

Be it known that I, CHARLES GUNNAR MOLIN, of Brooklyn, Kings county, New York, have invented a new and useful Improvement in Measuring Apparatus for Liquids, of which the following is a specification.

The object of my invention is to measure out liquids from bottles—as, for example, medicine or chemical reagents, which it is necessary to gage with accuracy.

My invention consists in the combination of a bottle or other similar receptacle for the liquid, provided with means for ejecting said liquid, with a measuring-vessel into which said liquid is received, all as hereinafter more particularly set forth.

In the accompanying drawings, Figure 1 is a vertical section of my device on the line xx of Fig. 2. Fig. 2 is a plan view of said device.

Similar letters of reference indicate like parts.

A is a bottle or any other similarly-shaped receptacle for the liquid. Extending downward into said bottle is a tube, B, which is secured in any suitable way to the lower part of the throat or neck to form a downward prolongation of the same. At the upper portion of the bottle is an opening, C, at which point is arranged an elastic bulb, D, of rubber or equivalent material. As shown, I prefer to surround the opening C with a rim, E, for convenient application of the bulb D. In said bulb is an opening, F, closed by a valve, G, which opens inward.

The throat of the bottle is made conical to receive the similarly-formed projection H on the bottom of the measuring-receptacle I. This projection forms the conical seat of a valve, J, which is prevented from escaping into the body of receptacle I by a fixed bar, K, extending across the bottom above said seat. The receptacle I is preferably made of glass, and upon its side is inscribed a scale or scales of any suitable graduation—as for drams or spoonfuls. For convenience, the receptacle I is also provided with a handle, L, and a spout, M, from which the contents may be poured or taken into the mouth.

The operation of the device is as follows: The parts being arranged substantially as

shown, on compressing the bulb D the air-pressure, so increased within the bottle, forces the liquid up the tube B and past the valve J, which it lifts, and so into the receptacle I. 55 As soon as the level of the liquid attains the desired point on the scale inscribed on the receptacle I, pressure is relaxed on the bulb D, which again expands, the valve G then opening. The valve J then returns to its seat. 60 The receptacle I may then be lifted out of the bottle, the valve J being retained closed by the liquid pressure above it. The liquid is then used as desired.

It will be seen that this device affords a 65 very convenient and accurate means of measuring any liquid directly from its containing vessel without tilting the latter or in any wise pouring the liquid therefrom. It is especially useful in the administration of medicines, especially such as require precise admeasurement, as it entirely does away with dropping or the use of such variable and erroneous measures as teaspoons or other articles of domestic use. The contents of the bottle are always 70 protected from access of the air, and with certain solutions the device is especially advantageous, inasmuch as all shaking or disturbance of the liquid is prevented.

I claim—

1. The combination, with the bottle A, having a tube, B, secured to the lower portion of its throat and extending into said bottle, and a bulb, D, also communicating with the interior of said bottle, of a detachable liquid-receptacle, I, having at its bottom a tubular projection, H, constructed to fit in said throat, and a valve, J, in said projection, substantially as described.

2. The combination, with the bottle A, having a tube, B, secured to the lower portion of its throat and extending into said bottle, and a bulb, D, having a valve, G, and communicating with the interior of said bottle, of a detachable liquid-receptacle, I, having at its 95 bottom a conical tubular projection, H, constructed to fit in said throat, and a valve, J, in said projection, substantially as described.

CHARLES GUNNAR MOLIN.
